(57) CLAIM

The ornamental design for an inflatable football model as shown and described.

DESCRIPTION

FIG. 1 is a front view showing my new design;

FIG. 2 is a back view thereof;

FIG. 3 is a left side view thereof;

FIG. 4 is a right side view thereof;

FIG. 5 is a top view thereof;

FIG. 6 is a bottom view;

FIG. 7 is a left side perspective view; and,

FIG. 8 is a right side perspective view.

The evenly spaced broken lines depict portions of the inflatable football model that form no part of the claimed design.
